APPLIQUED FABRIC

Bernard Friedman and Sol Rosengarten,
New York, N. Y.

Application July 18, 1952, Serial No. 20,673

Term of patent 3½ years

(Cl. D3—9)

To all whom it may concern:

Be it known that we, Bernard Friedman and Sol Rosengarten, both citizens of the United States both residing at New York, in the county of New York and State of New York, have invented a new, original, and ornamental Design for an Appliqued Fabric, of which the following is a specification, reference being had to the accompanying drawing, forming part thereof.

In the drawing:

Fig. 1 is a top plan view of an appliqued fabric, showing my new design, which unit is repeated in a horizontal direction;

Fig. 2 is an edge elevational view of the appliqued fabric; and

Fig. 3 is a vertical sectional view, taken on line 3—3 of Fig. 1.

I claim:

The ornamental design for an appliqued fabric, as shown and described.

BERNARD FRIEDMAN.
SOL ROSENGARTEN.
